EDGAR H. MUMFORD, OF PLAINFIELD, NEW JERSEY; ROSE SKEEL MUMFORD
EXECUTRIX OF SAID EDGAR H. MUMFORD, DECEASED.

JOLT RAMMING-MACHINE.

1,259,658.

Specification of Letters Patent. Patented Mar. 19, 1918.

Application filed September 19, 1914. Serial No. 862,473.

To all whom it may concern:

Be it known that I, EDGAR H. MUMFORD, a citizen of the United States, residing at Plainfield, in the county of Union and State 5 of New Jersey, have invented certain new and useful Improvements in Jolt Ramming Machines, of which the following is a specification.

This invention relates to jolt ramming machines for ramming sand molds and the like, and it has for its primary object the provision of an improved jolt ramming machine in which shock to the foundry floor is substantially eliminated. My invention also 10 contemplates an improved form of hydraulic shock jolt ramming machine. Still another object resides in providing an improved apparatus whereby it is possible to effectively and uniformly jolt ram sand 15 molds of considerable superficial area.

The foregoing, together with such other objects as may hereinafter appear or are incident to my invention I attain by means of a construction which I have illustrated in 20 preferred form in the accompanying drawings, wherein—

Figure 1 is a side elevation of my improved machine with the mold table in section to more fully illustrate the parts; Fig. 30 2 is a section through my improved means for actuating the mold table; Figs. 3 and 4 are respectively a longitudinal and a transverse section of the power means employed; Fig. 5 is a view showing a mold table actuated by my improved device in which, however, only one hydraulic element is employed; Fig. 6 is an end elevation of a detail of my invention, and Fig. 7 is a sectional view taken on the line VII—VII of 35 Fig. 1.

Briefly stated, my invention consists in imparting a jolting movement to a mold supporting member or table through the medium of one or more hydraulic columns, that is, columns of liquid, acting against such supporting member or table. One embodiment of my invention is shown in the accompanying drawings and will now be described.

50 Referring to Fig. 1, it will be seen that I provide an anvil 7 which is preferably a heavy block of cast metal, carried on beams 8 which are yielding or yieldingly supported, or both, as for example, by the springs 45 9. Bolted to the top of the anvil are two

pairs of cylinders 10 arranged symmetrically at four simultaneous centers of percussion substantially at the corners of the anvil in the upper part of each of which a plunger 11 bearing against the lower face 60 of the mold table 12 is adapted to work. When the table is in lowered position, it rests upon the flanges 10^a formed on the upper parts of the cylinders 10. Opening into the chamber A of each cylinder is a 65 pipe 14 which leads to a pressure box 15. The individual chambers of the pressure box are connected to a source of liquid supply, such as a tank, 16, by means of the pipes 17 and manifold 18. The supply tank 16 is 70 located above the level of the cylinders so that the liquid has a gravity feed into the chambers A, which chambers are thus kept filled so as to provide what may be termed 75 hydraulic columns which serve to actuate the table, as will further appear.

Mounted in the pressure box 15, in individual communication with the pipes 14, are four movable members or plungers 23 which are packed as indicated at 25, so as to prevent leakage (see Fig. 7). Adjacent to the pressure box and connected thereto by means of the four bars 19 is a pneumatic ram 20 having a hammer 21 which is operated by fluid pressure or other power means, in any 80 85 preferred manner.

The operation of the device is as follows, assuming that the mold table is in the position indicated in Fig. 1: The hammer 21 is driven forward to strike the plungers 23 a 90 heavy blow, and these in turn act upon the liquid in the individual chambers of the pressure box, the pipes 14 and chambers A driving it forward, thereby suddenly raising the pressures of the hydraulic columns causing them to act upon and lift the table with 95 a jolt. The liquid in the pressure box escapes but very slightly into the tank 16 because of the needle valves 22, and, in case of overload on the mold table, which would 100 occasion excessive pressures, I provide safety valves 24 in the pipes 14. The blow on the plungers 23 transmitted through the hydraulic columns jolts the table with an effect on the sand analogous to that obtained in 105 the well known types of jolt rammer wherein the mold table and its associated parts are elevated and then allowed to drop to impact upon an anvil. Each plunger 23 communicates preferably with some individual pipe 110

so that the jolting impulse is transmitted uniformly to all the jolting devices regardless of any lack of uniformity in loading at percussion points. In the ordinary type of machine the ramming is effected by arresting the movement of the falling table as distinguished from imparting an upwardly directed blow to a stationary table. However, I have found by experience that I am enabled to ram molds effectively and with greater rapidity with my improved type of jolt ramming machine, and this with scarcely any perceptible shock to the earth from the resiliently supported anvil, the principle being that when an acceleration of a certain magnitude is given to the plungers 11, the resulting force acts and reacts equally upon the mold table and its load and the resiliently supported anvil 7 whose momentary accelerations are in inverse proportion to their masses. The shock on the foundry floor, due to the deflection of the anvil, may be taken up in several ways. For example, the anvil may be so arranged as to be capable of considerable range of movement upon its resilient support and this will reduce the shock to the floor in proportion to the time taken to stop it. On the other hand, the greater the mass of the anvil, the less will be the momentary velocity thereof and the shock to the floor will be less on this account, regardless of the amplitude of movement. The mass of the anvil, the mass of the hammer, and the force of the blow delivered by the latter may be varied to suit the character of the work to be done and the conditions of doing it.

Although other forms of power means may be employed to actuate the plungers 23, I prefer to use a pneumatic hammer having a long stroke so as to utilize the expansion of the air, thereby effecting an economy in air consumption.

It will be apparent that I can operate a mold table with a single column, but it will also be seen that by the use of my invention I am enabled to successfully, uniformly, and effectively jolt ram molds of very large dimensions, molds the superficial area of which would render it impossible to ram them with the ordinary jolt ramming machine. This can be done by providing a plurality of columns, terminating at different points under the mold table; for the blow delivered to the plungers 23 will be imparted through the different columns uniformly to these percussion points under the table, with a resultant uniformity in the ramming. By transmitting the blow through the water columns, it is possible to conveniently arrange the power means with reference to the mold table, regardless of the size of the latter or the number of columns.

The member 7 has been termed an anvil because it supports a cylinder or cylinders

10, and the hydraulic column reacts on the cylinder and the member 7 when the ram is operated, and thus imparts a jolting movement or impulse to the table 12 through the piston or pistons 11. In this sense therefore 70 the block 7 and its associated parts is an anvil-like member.

The foregoing advantages together with those incident to the substantial elimination of shock to the foundry floor, will be readily apparent to those skilled in the art to which this invention pertains.

I claim:—

1. A jolt ramming apparatus comprising in combination a mold-supporting member, 80 an hydraulic column arranged to act upon said member, and means for imparting a jolting impulse to the supporting member through the medium of the hydraulic column.

2. A jolt ramming apparatus comprising in combination a mold-supporting member, a plurality of hydraulic columns arranged to act upon said member, and means for imparting simultaneous jolting impulses to 90 the supporting member through the medium of the hydraulic columns.

3. A jolt ramming apparatus comprising in combination a mold-supporting member, an anvil, an interposed hydraulic column, 95 and means for imparting a jolting impulse to the supporting member through the medium of the hydraulic column.

4. A jolt ramming apparatus comprising in combination a mold-supporting member, 100 a yieldingly supported anvil, an interposed hydraulic column, and means for imparting a jolting impulse to the supporting member through the medium of the hydraulic column.

5. A jolt ramming apparatus comprising in combination a mold-supporting member, a plurality of hydraulic columns arranged to act upon said member, and a common means for imparting jolting impulses to the 110 supporting member through the medium of the hydraulic columns.

6. A jolt ramming apparatus comprising in combination a mold-supporting member, an hydraulic column arranged to act upon 115 said member, and means for imparting a jolting impulse to the supporting member through the medium of the hydraulic column, comprising a movable member acting upon the hydraulic column and adapted 120 when moved to raise the pressure on the column.

7. A jolt ramming apparatus comprising in combination a mold-supporting member, an hydraulic column arranged to act upon 125 said member, means for imparting a jolting impulse to the supporting member through the medium of the hydraulic column comprising a movable member acting upon the column and adapted when moved to raise 130

the pressure on the column, and a ram for delivering a blow to said movable member.

8. A jolt ramming apparatus comprising in combination a mold-supporting member, a plurality of hydraulic columns arranged to act upon said member, a movable member acting upon each column to impart therethrough a jolting impulse to the supporting member, and common means for simultaneously delivering a blow to each of said movable members.

9. A jolt ramming apparatus comprising in combination a mold-supporting member, a plurality of hydraulic columns arranged to act upon said member, a movable member acting upon each column to impart therethrough a jolting impulse to the supporting member, and a ram for simultaneously delivering a blow to each of said movable members.

10. A jolt ramming apparatus comprising in combination a mold-supporting member, an anvil, a plurality of interposed hydraulic columns arranged to act upon said members, a movable member acting upon each column to impart therethrough a jolting impulse to the supporting member, and common means for simultaneously deliver-

ing a blow to each of said movable members.

11. A jolt ramming apparatus comprising in combination a mold-supporting member, a yieldingly supported anvil, a plurality of interposed hydraulic columns arranged to act upon said members, a movable member acting upon each column to impart therethrough a jolting impulse to the supporting member, and common means for simultaneously delivering a blow to each of said movable members.

12. In jolt ramming apparatus, a plurality of hydraulic columns, and a common means for simultaneously imparting jolting impulses thereto.

13. In jolt ramming apparatus, a plurality of hydraulic columns, and a common means for imparting jolting impulses to each column independently of the other columns.

In testimony whereof I have hereunto signed my name in the presence of the two subscribed witnesses.

EDGAR H. MUMFORD.
